UNITED STATES PATENT OFFICE.

RICHARD G. KENNEDY, OF MORRIS, TEXAS.

DESIGN FOR A CHAIR.

50,066.

Specification for Design.

Patented Dec. 19, 1916.

Application filed September 23, 1916. Serial No. 121,890. Term of patent 14 years.

To all whom it may concern:

Be it known that I, RICHARD G. KENNEDY, a citizen of the United States, residing at Morris, in the county of Howard and State of Texas, have invented a new, original, and ornamental Design for Chairs, of which the following is a specification, reference being had to the accompanying drawing, forming part thereof.

The figure is a perspective view of a chair, showing my new design.

I claim:

The ornamental design for a chair, as shown.

RICHARD G. KENNEDY.

Witnesses:

C. L. ALDERMAN,
W. G. HAYDEN.
